DESIGN FOR A BOW LABEL

Peter L. Forsman, New York, N. Y., assignor to Elmo Sales Corporation, Philadelphia, Pa.

Application June 11, 1941, Serial No. 101,403

Term of patent 14 years

To all whom it may concern:

Be it known that I, Peter L. Forsman, a citizen of the United States, residing at New York, county of New York and State of New York, have invented a new, original, and ornamental Design for a Bow Label, of which the following is a specification, reference being had to the accompanying drawing, forming part thereof.

Fig. 1 is a plan view of a bow label showing my new design; and

Fig. 2 is an edge elevational view of the same.

I claim:

The ornamental design for a bow label, as shown.

PETER L. FORSMAN.
